United States Patent Office

Des. 187,570
Patented Mar. 29, 1960

187,570

LIST FINDER

Kenneth M. White, Westwood, N.J., assignor to Zephyr American Corporation, New York, N.Y., a corporation of New York

Application January 27, 1959, Serial No. 54,356

Term of patent 14 years

(Cl. D74—1)

Fig. 1.

Fig. 2.

Fig. 1 is a side perspective view of a list finder, showing my new design; and

Fig. 2 is an elevational view thereof showing the side opposite to that of Fig. 1.

I claim:

The ornamental design for a list finder, as shown.
